UNITED STATES PATENT OFFICE

167,287

CHILD'S AUXILIARY SEAT

James Wright Smith, Austin, Tex.

Application November 19, 1951, Serial No. 17,474

Term of patent 14 years

(Cl. D15—1)

To all whom it may concern:

Be it known that I, James Wright Smith, a citizen of the United States, residing at Austin, State of Texas, have invented a new, original, and ornamental Design for Child's Auxiliary Seat, of which the following is a specification, reference being had to the accompanying drawing, forming a part hereof.

Fig. 1 is a perspective view of a child's auxiliary seat, showing my new design;

Fig. 2 is a bottom perspective view of the child's auxiliary seat; and

Fig. 3 is a side view thereof.

I claim:

The ornamental design for a child's auxiliary seat, as shown.

JAMES WRIGHT SMITH.
